Atty.

UNITED STATES PATENT OFFICE.

WILLIAM DALLAS BROWN, OF SCHOOLFIELD, VIRGINIA, ASSIGNOR TO DRAPER CORPORATION, OF HOPEDALE, MASSACHUSETTS, A CORPORATION OF MAINE.

THREAD-CUTTING TEMPLE FOR LOOMS.

Application filed February 2, 1925. Serial No. 6,342.

This invention relates to thread cutting temples for looms. Such devices have long been employed in connection with automatic filling replenishing looms for the purpose of severing close to the selvage the filling ends left protruding therefrom after replenishment of filling takes place.

The present invention relates more particularly to that type of thread cutting temple in which the cutting mechanism carried by the temple includes a fixed cutter blade and a rotary cutter blade actuated by the temple roll.

The object of the invention is to provide a simple and efficient form of construction of this latter type and one which will sever the filling end with a clean cut whenever a filling end is brought into its field of action.

The nature and object of the invention will appear more fully from the accompanying description and will be particularly pointed out in the claims.

Thread cutting temples, including those of the rotary type, being well known and familiar to those skilled in the art, it is only necessary here to illustrate and describe those parts directly concerned with the present invention. In the drawings, therefore, there is illustrated, apart from the loom, a device embodying a simple and preferred form of the invention.

In the drawings:

Fig. 1 is a right hand side elevation of a temple, partially broken away, such as is employed at the right hand side of the loom.

Fig. 2 is a detail of the construction shown in Fig. 1, chiefly in transverse vertical cross section, taken on the line 2—2 of Fig. 3.

Fig. 3 is a view in elevation looking toward the front of the construction shown in Fig. 1.

Fig. 4 is a detail in cross section taken on the line 4—4 of Fig. 2.

Fig. 5 is a side elevation of the fixed or stationary cutter blade.

The temple illustrated is of that type employing two toothed rolls, but the present invention is not limited to the number or arrangement of the rolls. The shank 1 of the temple is mounted for rectilinear yielding movement in the usual manner in the temple stand 2. At its rearward end the shank 1

merges into the head or main body portion 3 of the temple. This head has laterally extending therefrom toward the center of the loom the usual cap 4 and the usual pod 5. The cap and pod are spaced apart to provide for the passage of the cloth therebetween. Secured to or formed upon a suitable portion of the head or pod is the usual depending heel 6, which is struck by the lay of the loom upon the beat-up to move the entire temple bodily forward against the action of its spring, which upon rearward movement of the lay returns the temple to its normal position.

The cap 4 is shown as a separate piece secured to the head by a set screw 7.

The toothed rolls 8 and 9 may be of any suitable construction and are shown as of the usual wooden cylindrical type provided with the pin points 10. The forward roll 9 is journalled on a spindle 11 threaded into the head 3 of the temple at one end and supported at the other end in the pod. The rear roll 8 is similarly mounted on the spindle 12. This spindle is also threaded at 13 into the head 3 of the temple, while its other end is supported at 14 in the pod.

The cutting mechanism is located in a transverse slot 15 formed in the head of the temple adjacent the end of the roll 8. This slot opens at the rear of the temple and is closed at the front by the edge wall 16. The outer end of the roll 8 projects through the head of the temple to the lateral wall 17 of this slot which therefore surrounds the forward end of the roller 8. The temple roll at this end is preferably provided with a metal ferrule 18 having a central re-entrant polygonal socket 19.

The cutting mechanism comprises two thin metal, preferably steel, blades. One of these is a circular knife blade 20 presenting at its periphery a continuous series of teeth 21 which are preferably symmetrical with respect to the radius of the blade and which also are bevelled off at the inner surface, as shown in Fig. 4. This circular toothed knife blade is centrally apertured to fit over the spindle 12 and is provided with a polygonal hub 23 fitting into the re-entrant socket 19 of the ferrule 18 on the end of the roll 8. It will be seen, therefore, that the circular knife blade rotates with the temple

roll and that its inner surface abuts against the flat, circular, lateral wall 17 of the slot 15.

- 5 The stationary knife blade 24 is shown separately in Fig. 5 and is preferably of a generally rectangular shape. It is provided with an aperture 25 fitting over the spindle 12 and is of such a size that one of its edges abuts the edge wall of the slot 15 so as to prevent 10 rotation of the knife blade and hold it stationary. As shown, the forward edge 26 of the knife blade abuts the forward edge wall 16 of the slot 15. At its rear edge the stationary knife blade is provided 15 with a notch 27, the lower edge of which, and preferably both the upper and lower edges of which, form cutting edges to cooperate with the teeth of the circular knife blade.
- 20 A filling end guiding groove is formed in the rear face of the head in alignment with the space between the cap and pod and forms a continuation of this space. The stationary knife blade 24 is mounted so that its 25 notch 27 is in alignment with this filling end guiding groove.

Suitable means are provided which act 30 yieldingly to maintain the stationary knife blade in close contact with the circular 35 blade. For that purpose the head is provided with an annular socket 29 surrounding the spindle 12 and opening into the slot 15. A helical spring 30 is seated in this 40 socket abutting the end of the spindle at one end and the surface of the stationary blade 24 at the other end, and thus acts to press the stationary blade snugly against the circular blade and insure a clean shearing action when the circular blade is rotated in either direction.

It will thus be seen that any filling end 45 extending from the cloth and guided into the filling end guiding slot 28 is also guided into the notch 27 and consequently brought into the field of action of the cutting mechanism. Consequently as the roll is rotated by the reciprocating movement of the temple with respect to the cloth, the circular knife 50 blade is simultaneously rotated and one or the other of the edges of its teeth act in cooperation with one or the other of the edges of the notch 27 of the stationary blade to sever the filling end.

The construction is one that is easily made 55 and assembled in the temple. The cutting blades may have a loose fit and all that is necessary is that their juxtaposed surfaces shall be flat and smooth because the spring acts to press them into close contact and thus insure the cooperative shearing action 60 under all conditions.

Having thus described the invention, what

is claimed as new, and desired to be secured by Letters Patent, is:

1. A thread cutting temple for looms comprising a head having a laterally extending spaced cap and pod, a roll spindle threaded at one end in the head, a toothed roll journalled on the spindle, a transverse rearwardly opening slot in the head adjacent the roll end, the said slot presenting fixed vertical lateral opposed walls, a filling end guiding groove in the rear face of the head in alignment with the space between the cap and pod and forming a continuation thereof across the slot, a circular knife blade mounted in the slot on the spindle, keyed to the roll to rotate therewith and abutting the flat face of the lateral wall of the slot adjacent the roll end, a stationary knife blade mounted in the slot on the spindle, abutting the edge wall of the slot and thereby held against rotation and having in its rear edge a notch in alignment with the filling end guiding groove, the edge of this notch cooperating with the edges of the teeth of the circular knife blade when rotated to shear off filling ends guided into the notch, and means acting yieldingly to maintain the stationary knife blade in close contact with the circular blade and also acting to force the circular blade against the flat face of the lateral wall of the slot.

2. A thread cutting temple for looms comprising a head having a laterally extending spaced cap and pod, and a depending heel which is struck by the lay of the loom upon its bet-up, a roll spindle threaded at one end in the head, a toothed roll journalled on the spindle, a transverse rearwardly opening slot in the head adjacent the roll end, a filling end guiding groove in the rear face of the head in alignment with the space between the cap and pod and forming a continuation thereof across the slot, a circular knife blade presenting radially symmetrical peripheral teeth mounted in the slot on the spindle, keyed to the roll to rotate therewith and abutting the lateral wall of the slot, a stationary knife blade mounted in the slot on the spindle abutting the edge wall of the slot and thereby held against rotation and having in its rear edge a notch in alignment with the filling end guiding groove, both edges of this notch cooperating with the edges of the teeth of the circular knife blade when rotated in either direction to shear off filling ends guided into the notch, and means acting yieldingly to maintain the stationary blade in close contact with the circular blade.

In testimony whereof, I have signed my name to this specification.

WILLIAM DALLAS BROWN.
